UNITED STATES PATENT OFFICE

MAX M. SUPPES, OF ELYRIA, OHIO, ASSIGNOR TO THE FOX FURNACE COMPANY, OF ELYRIA, OHIO, A CORPORATION OF OHIO

HINGE

Application filed March 15, 1929. Serial No. 347,202.

My invention relates to new and useful improvements in closure structures, and more particularly to the closure supporting means.

An object of my invention is to provide means whereby a closure member may be readily attached to and removed from its supporting structure.

Another object is to provide a supporting means which is concealed from view when the closure member is in closed position.

The invention consists in the improved construction and combination of parts, to be more fully described hereinafter, and the novelty of which will be particularly pointed out and distinctly claimed.

In the accompanying drawings, forming a part of this specification, I have fully and clearly illustrated a preferred embodiment of my invention, in which drawings

Figure 1 is a front elevation of the structure;

Fig. 2 is a rear view in elevation of a detail of Fig. 1;

Fig. 3 is a view in section on the line 3—3 of Fig. 1;

Fig. 4 is a detail view in section on the line 4—4 of Fig. 3;

Fig. 5 is a detail view similar to Fig. 4, but showing the closure member in open position, and

Fig. 6 is a detail view of a hinge member.

Referring to the drawings by characters of reference, 1 designates, generally, a structure embodying my invention. For the purpose solely of illustration, I have shown the structure 1 as a portion of a heating apparatus of the type having an enclosing jacket. The apparatus may be mounted on a base 2 having corner legs 3 and cross rails 4. The casing 5 of the ash-pit rests upon the rails 4 which support the apparatus. The front of the casing 5 is open and secured thereto, as by bolts 6, or the like, is a supporting plate-like frame member 7 having the usual door or closure opening 8 for access to the ash-pit. The

member 7 is substantially rectangular, having horizontal top and bottom members 9, 10, respectively, which are joined by vertical side members 11, 12. Extending forwardly from the member 7 at the marginal edge of the opening 8, is a surrounding flange 13. That portion, designated 14, of the flange 13 which extends along the side member 12, is recessed on its rear side and provides downward and upward facing shoulders 15, 16, respectively. Through the side member 12 is a substantially rectangular opening 17 of a height substantially equal to the distance between the shoulders 15 and 16. Surrounding the opening 17 is a forwardly projecting wall member comprising substantially parallel vertical side portions 18, 19, which are joined by top and bottom portions 20, 21, respectively. The side portion 18 which extends substantially parallel to and adjacent the portion 14 of flange 13 is recessed on its rear side for substantially its full length or height. Joining the side portion 18 and the top and bottom portions 20, 21 to the flange portion 14, is a bridging portion 22 which is substantially U-shaped and serves to close the space between the wall member and the flange portion 14. The opening 17 is closed by a plate member 23 which is secured to the front face 24 of the wall member by means of screws 25, or the like. Extending across the opening 17 adjacent the upper and lower ends thereof are substantially horizontal plate members 26, 27, respectively, which also extend forward a distance substantially equal to that of the wall portions. The portion 22 has on its rear face and adjacent to but below the member 26, a hook or locking member 28, which comprises a substantially horizontal part 29 from the free end of which extends upward a part or arm 30. The opening 8 is adapted to be closed by a door or closure member 31 having a hinge member 32 which preferably comprises a pair of spaced arm members 33, 34, which may

be joined by a bar member 35 at their door member-engaging ends. The hinge member 32 is preferably secured to the door member by bolts, or the like 36. The arm members 33, 34 project through the opening 8, and each preferably comprises a substantially arcuate portion, designated, respectively, 37, 38, extending from the door member, and a portion designated, respectively, 39, 40, substantially radial to its arcuate portion. The portions 39, 40 terminate in bearing parts 41, 42. The portions 39, 40 are of such length that when the door member is in closed position, the bearing parts 41, 42 will lie between the plate member 26 and wall portion 20 and between plate member 27 and wall portion 21, respectively. Through the plate member 26, bearing part 41, and wall portion 20, are substantially vertically aligned apertures 43, 44, 45, respectively. Through the plate members 27, bearing part 42, and wall portion 21, are substantially vertically aligned apertures 46, 47, 48, respectively. Extending through the apertures 43, 44, 45, is a hinge pin or pintle 49 which is supported by the wall portion 20 and plate member 26, and which in turn supports the hinge arm 33. The pin 49 is held or locked in position by a member or arm 50 which extends laterally therefrom at its inner and lower end and seats on the hook part 29 between the hook part 30 and the portion 22. Extending through the apertures 46, 47, 48 is a hinge pin or pintle 51 having an eye 52, or other enlargement, at its inner and upper end, and which seats on the plate member 27. The plate member 27 and wall portion support the pin 51, which in turn supports the hinge arm 34. The apertures 44 and 47 are of sufficient diameter to permit free swinging of the hinge member on its pintles. If desired, washers 52', or the like, may be placed between the arm member 33 and plate member 26 and between the arm member 34 and the wall portion 21.

In order to remove the closure member 31 from the supporting frame member 7, the plate member 23 is removed by unscrewing the screws 25, provided the enclosing jacket 53 is not in place; but if such is the case, the door may be swung to open position, as in Fig. 5. In either case, access may be had to the pins 49 and 51. Removal of pin 51 merely requires that it be vertically withdrawn, as is apparent. Removal of pin 49, however, requires that the pin be lifted or moved from its normal position, designated A, Fig. 2, further into or through the apertures 43, 44, 45 until the lateral arm 50 is above the upright arm 30, as indicated by the dotted line position designated B, and then swung forward from the plane of the drawing, Fig. 2, or from right to left of Fig. 3, so that arm 50 will be out of opposing relation to the hook member 28, whereupon the pin 49 may be withdrawn by downward movement from the

apertures 46, 47, 48, thus freeing the door from the supporting frame member. To mount the door on the supporting frame member merely requires a reversal of the above outlined steps by which the pins 49 and 51 are removed. 70

What I claim and desire to secure by Letters Patent of the United States is:

1. In a heating apparatus, a door frame having top, bottom and side frame members, one of said side frame members having substantially horizontal spaced members, an upwardly facing hook member positioned beneath said spaced members, said spaced members having aligned bearing apertures therethrough offset horizontally from said hook member, a closure member cooperable with said frame and having a hinge arm rigid therewith, the free end of said arm extending between said spaced members and having an aperture aligned with said apertures, a hinge pin longitudinally reciprocable in said apertures and having a lateral arm cooperative with said hook member whereby said pin is held against withdrawal from said apertures. 80 85 90

2. In a heating apparatus, a door frame having top, bottom and side frame members, a closure member cooperable with said members, a hinge member having vertically spaced substantially parallel arms and being rigidly secured to said closure member, a bar member rigidly connecting said arms at said closure member, spaced substantially horizontal hinge pin receiving members rigid 100 with said frame and lying respectively above and below each of said arms, a hinge pin extending through each of said arms and its adjacent pin receiving members, and means normally preventing withdrawal of one of 105 said pins. 95

3. In a heating apparatus, a cast metal door frame having top, bottom and side frame members, one of said side frame members having an aperture therethrough with a surrounding flange, a plate portion extending across said aperture adjacent and substantially parallel to the top portion of said flange, a closure member cooperable with said frame and having a hinge member, the free end of said hinge member extending into said aperture between said flange and plate portion, and a hinge pin extending through said plate portion, said hinge member and said flange whereby to provide a pintle for 120 said closure member. 110 115 125

4. In a heating apparatus, a cast metal door frame having top, bottom and side frame members, one of said side frame members having an aperture therethrough with a surrounding flange, a plate portion extending across said aperture adjacent and substantially parallel to the top portion of said flange, an upwardly facing hook member rigid with said one side member and posi- 130

tioned below said plate portion, a closure member cooperable with said frame and having a hinge member, the free end of said hinge member extending into said aperture between said flange and plate portion, and a hinge pin extending through said plate portion, said hinge member and said flange whereby to provide a pintle for said closure member, said pin having a lateral arm cooperative with said hook member.

In testimony whereof I have hereunto signed my name.

MAX M. SUPPES.
